UNITED STATES PATENT OFFICE.

THOMAS A. PEARCE, OF PHILADELPHIA, PENNSYLVANIA.

DESIGN FOR THE ORNAMENTATION OF KNITTED SHIRTS.

SPECIFICATION forming part of Design No. 19,298, dated September 3, 1889.

Application filed June 10, 1889. Serial No. 313,750. Term of patent 7 years.

To all whom it may concern:

Be it known that I, THOMAS A. PEARCE, a citizen of the United States, residing in the city and county of Philadelphia, State of Pennsylvania, have invented and produced a new and original Design for a Knitted Shirt, of which the following is a specification, reference being had to the accompanying drawing, forming part thereof.

10 The leading feature of my design for the surface ornamentation of a knitted shirt is a row of parallel stripes thereon, said stripes being of different widths.

In the drawing, A designates a knitted

shirt having parallel side stripes B B'. The 15 stripe at the center of the shirt is broad, and the stripes at the side are gradually narrower.

I claim—

A design for the ornamentation of a knitted shirt, consisting of a broad central stripe 20 and parallel side stripes, the side stripes being of gradually diminishing width, substantially as shown and described.

THOMAS A. PEARCE.
